AUTOMATICALLY THREADING LOOM SHUTTLE

Filed Feb. 25, 1930

UNITED STATES PATENT OFFICE

CLARE H. DRAPER, OF HOPEDALE, MASSACHUSETTS, ASSIGNOR TO DRAPER CORPORATION, OF HOPEDALE, MASSACHUSETTS, A CORPORATION OF MAINE

AUTOMATICALLY-THREADING LOOM SHUTTLE

Application filed February 25, 1930. Serial No. 431,155.

This invention relates to automatically threading loom shuttles wherein the filling in the shuttle is changed from time to time, and is more particularly directed to the 5 means for imparting tension to the thread throughout the weaving operation.

It has heretofore been proposed to provide an automatically threading loom shuttle with a rigid arm extending longitudinally of the 10 thread passage and about which the thread is passed on the first pick of the shuttle following replenishment, and in some cases the rigid arm has had a thread director or scroll for guiding the swirling thread in its circu- 15 lar path to wrap the thread about the rigid arm.

During the weaving operation, however, it frequently happens that a loop of thread is thrown forwardly or towards the threading 20 end of the shuttle as the latter comes to rest in the shuttle box, and in such cases the loop of thread, whether it be caused by an over-throw or by a coil of thread thrown forwardly from the filling carrier or bobbin, will 25 become fouled with the thread director to such an extent as to cause thread breakage on subsequent picks of the shuttle, and even though thread breakage does not occur there will result a variation in thread tension which 30 will be reflected in the finished cloth.

In the broad aspect of the present invention the tensioning effect upon the thread is secured by a tensioning member extending longitudinally of the thread passage and 35 about which the thread is caused to be wrapped by an elongated spiral or helix protected from engagement with the thread by a guard substantially surrounding or enclosing the coils of the spiral or helix adjacent the 40 bobbin chamber, so that should a loop or coil of thread be thrown towards the threading end of the shuttle, it will be intercepted by the guard and prevented from passing circumferentially about or between the coils of the 45 elongated spiral or helix.

The invention and novel features thereof will best be made clear from the following description and the accompanying drawings of one good form thereof.

50 In the drawings:

Fig. 1 is a plan view of an automatically threading shuttle containing the present invention, the bobbin holding end of the shuttle being broken away;

Fig. 2 is a section on the line 2—2 of Fig. 1; 55 and

Fig. 3 is a perspective view with parts broken away showing the present invention with the shuttle fully threaded.

Automatically threading loom shuttles are 60 usually provided with bobbin holding jaws which permit ejection of a spent carrier and the introduction of another carrier having filling thread wound thereon, but since these parts are now well understood in the art they 65 are not herein shown and described.

In the drawings the shuttle 1 has a bobbin chamber 2 in which is detachably supported the bobbin or filling carrier 3, and forward of the bobbin chamber the shuttle is provided 70 with the longitudinal thread passage 4 and the side delivery eye 5 which communicates therewith.

Automatically threading loom shuttles are 75 now usually provided with a device at the delivery end of the shuttle for facilitating automatic threading during the loom operation, and so far as the present invention is concerned such device may be of any of the usual types now well-known, except as modified in accordance with the present invention.

As shown, the shuttle is provided with a threading block 6 in which is formed the longitudinal thread passage 4 into which the 85 thread passes when the shuttle is replenished with filling. The threading block may also be provided with a thread director 7 between which and the wood of the shuttle a passageway 8 is formed leading to the side 90 delivery eye, and as shown, also, in the present instance of the invention, the leading end of the thread director 7 is provided with a guard 9 which may overlie the end of the thread director. The parts so far described 95 are old and well-known and may be of any of the usual types of threading blocks.

Extending longitudinally of the thread passage is the thread tensioning member 10 which, as shown in the present instance of the 100

invention, has its end 11 which is remote from the bobbin chamber secured to the shuttle or threading block, and about the tensioning member 10 which is constituted as an arm, preferably of yielding character, in order to yield with the pull of the thread, the thread is passed an appropriate number of turns to impart the desired tension thereto.

In order that the thread may be directed about the thread tensioning member 10 on the first pick of the shuttle following replenishment, the present invention contemplates an elongated spiral or helix which serves to guide the thread about the tensioning member as the thread is withdrawn from the shuttle.

The helix 12, as shown, is mounted forward of the bobbin chamber and has the end 13 thereof secured in fixed position, so that as the shuttle is picked, the swirling thread will follow the convolutions or spirals of the helix and wrap about the tensioning member, as more clearly indicated in Fig. 3.

Associated with the helix 12 is a helix guard which surrounds the coils of the helix at sufficient distance therefrom to permit the swirling thread to pass about the coils of the helix between it and the guard and yet prevent any loop or overthrow of thread from improperly engaging the coils of the helix.

The helix guard may be variously contrived but as shown in the present instance of the invention it is formed on the threading block and comprises the enclosing members 14 and 15, the inner curved surface 16 of which is closely adjacent to and encloses the larger coils of the helix on all sides adjacent to the bobbin chamber, as more clearly shown in Fig. 2. To permit the filling thread to pass downwardly into the longitudinal thread passage 4 when filling is replenished a small opening 17 is formed between the members 14 and 15 of the helix guard.

In the preferred form of the invention as illustrated, the longitudinally extending tensioning member 10 is yieldable under the pull of the thread by reason of its connection with the helix and the leading end of the shuttle or threading block as indicated in Fig. 3. It will be noted that the thread *a* leads laterally from the tensioning member 10 about a guide post or other suitable guide 18 towards the side delivery eye, and should the tension of the thread exert a pull laterally upon the tensioning member 10, as the thread is delivered from the shuttle, the tensioning member is free to yield with the thread to maintain uniform tension and then by reason of its yieldability to return to its normal position again to take up any slack that may have occurred in the thread.

As shown in the present instance of the invention, the helix 12 is mounted in the longitudinal thread passage at the end thereof adjacent the bobbin chamber and its smaller

coils extend from this point forwardly towards the opposite end of the thread passage.

The helix guard constitutes an important feature of the present invention in preventing any loop or overthrow of thread engaging about the coils of the helix, and if a loop of thread somewhat larger than the outer coil of the helix should be thrown forwardly when the shuttle is arrested in the shuttle box, the helix guard will prevent such loop or overthrow of thread from engaging about the coils of the helix, and when the shuttle is subsequently picked, any slack thread will remain in its normal threaded position through the helix. The helix guard which encloses or surrounds at least the larger coils of the helix is only sufficiently large relative to the helix coils to permit the swirling thread to be guided about the longitudinally extending tensioning member 10 as the shuttle is picked, and yet not large enough to permit any loop or overthrow of thread from becoming fouled with the coils of the helix. Should the loop of thread be thrown forwardly as the shuttle comes to rest in the shuttle box and engage the central portion of the helix, no harm results, either to the thread or the tension thereon, because the helix will retain the thread centrally and prevent its spreading about the coils which extend towards the end of the thread passage remote from the bobbin chamber.

From the construction described as one good form or embodiment of the present invention, it will be evident that a tensioning device is provided embodying elongated spiral coils or a helix for guiding the thread about the tensioning member when the shuttle is picked following replenishment and a guard is provided for the helix which practically surrounds the latter and prevents any loops of thread from becoming entangled or fouled with the spirals of the helix throughout the weaving operation.

In the form of the invention shown, the tensioning member 10 which extends longitudinally of the thread passage is formed as a part of the helix, the smaller coils of which merge into the tensioning member, and while this is a good practical form of the invention, it may be varied in these respects without departing from the true scope of the invention. Likewise, while the tensioning member is shown as having its end remote from the bobbin chamber secured to the shuttle or threading block, this may not always be necessary, the essentials being that a surrounding guard be provided for the coils of the helix to prevent any loop or overthrow of thread from fouling the coils of the helix or becoming entangled therewith, so that during the entire weaving operation the same tension will be maintained, and the thread led direct from the bobbin chamber about the tensioning member to the side delivery eye.

What is claimed is:

1. An automatically threading loom shuttle having a bobbin chamber, a longitudinal thread passage and a side delivery eye communicating therewith, a thread tensioning member extending longitudinally of the thread passage, an elongated spiral for directing the thread about the tensioning member, and a protecting guard extending about and over the top of the elongated spiral to prevent the thread from entanglement with the elongated spiral during weaving. 5
2. An automatically threading loom shuttle having a bobbin chamber, a longitudinal thread passage and a side delivery eye, a thread tensioning member constituted as an arm extending longitudinally of the thread passage, a helix for directing the thread about the said arm as the shuttle is picked following replenishment, and a helix guard extending laterally of the thread passage and over the top of the helix and acting to prevent the thread from fouling the coils of the helix during subsequent weaving. 10
3. An automatically threading loom shuttle having a longitudinal thread passage, a thread tensioning member constituted as an arm extending longitudinally of the thread passage and yieldably responsive to the lateral pull of the thread to maintain tension thereon and take up slack, a helix for directing the thread about the yieldable arm on the first pick of the shuttle following replenishment, and a protecting guard extending laterally of the thread passage and about the helix and acting to prevent coils of thread from encircling the helix during subsequent weaving. 15
4. An automatically threading loom shuttle having a bobbin chamber, a longitudinal thread passage and side delivery eye, a thread tensioning member constituted as an arm extending longitudinally of the thread passage, a helix, the tapering coils of which extend towards the end of the longitudinal passage remote from the bobbin chamber for directing the thread about the tensioning member, and a helix guard extending about the larger coils of the helix and acting to protect the coils of the helix from improper engagement by a loop of thread during weaving. 20
5. An automatically threading loom shuttle having a bobbin chamber, a longitudinal thread passage and delivery eye, a helix having its smaller coils extending toward the end of the longitudinal thread passage remote from the bobbin chamber, a thread tensioning member extending from the helix longitudinally of the thread passage and about which the thread is directed by the helix as the shuttle is picked, and a helix guard extending about and over the larger coils of the helix to prevent loops of thread formed during weaving from engagement about the coils of the helix. 25
6. An automatically threading loom shuttle having a bobbin chamber, a longitudinal thread passage and delivery eye, a helix having its smaller coils extending toward the end of the longitudinal thread passage remote from the bobbin chamber, a thread tensioning member constituted as an arm extending from the helix longitudinally of the thread passage and about which the thread is directed by the helix as the shuttle is picked, said arm being yieldable in response to the pull of the thread to maintain uniform tension thereon and take up slack and a helix guard to prevent loops of thread formed during weaving from engagement about the coils of the helix. 30
7. An automatically threading loom shuttle having a bobbin chamber, a longitudinal thread passage and a delivery eye, a thread tensioning member extending longitudinally of the thread passage, a helix having its tapering coils extending towards the end of the thread passage remote from the bobbin chamber for directing the thread about the tensioning member, and a helix guard extending about and over the top of the helix in such proximity to the coils of the helix as to permit the thread to pass between the guard and helix as the shuttle is picked following replenishment and prevent loops of thread from thereafter fouling the coils of the helix. 35
8. An automatically threading loom shuttle having a bobbin chamber, a longitudinal thread passage and a delivery eye, a thread tensioning member constituted as an arm extending longitudinally of the thread passage, and laterally flexible in response to the pull of the thread to maintain tension thereon and take up slack, a helix having its tapering coils extending towards the end of the thread passage remote from the bobbin chamber for directing the thread about the tensioning member, and a helix guard extending about and over the helix in such proximity to the coils of the helix as to permit the thread to pass between the guard and helix as the shuttle is picked following replenishment and prevent loops of thread from thereafter fouling the coils of the helix. 40

In testimony whereof, I have signed my name to this specification.
